DES. 2143

Franklin Simmons, of Washington, D.C.
As for to
William Miller, of Providence, R.I.
Letters Patent No. 2138 - Dated July 8 - 1865.
Design for a Medallion of Maj. Gen. Wright.

The schedule referred to in these letters Patent and making part of this same.

To all whom it may concern.

Be it known that Franklin Simmons, of the city of Washington, D.C. have originated and produced a new model, of which the accompanying photograph is a true representation.

What I claim as my invention or production, and desire to secure by letters Patent is The design for my exclusive Portrait of Maj. Gen. Wright represented by the photograph herewith attached.

Witnesses.

Edm. F. Brown.
Peter Baumgras.
